UNITED STATES PATENT OFFICE.

HALLETT O. NORMAN, OF COUCH, OREGON.

FLYING MACHINE.

Application filed December 28, 1927. Serial No. 243,143.

This invention relates to improvements in flying machines, the general object of the invention being to provide means for retarding the falling of the craft, if anything 5 should happen to the same, by an arrangement which acts as a parachute for the craft.

Another object of the invention is to so arrange the parts that they normally lie in a plane in alignment with one of the planes 10 of the craft and form extensions of such plane, with manually operated means for tilting such parts downwardly to form with the plane a parachute-like device.

This invention also consists in certain other 15 features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a side view of the improved craft.

Figure 2 is a front view.

Figure 3 is a similar view with the parts in operative position.

30 Figure 4 is a plan view.

Figure 5 is an enlarged sectional view.

Figure 6 is a view of one corner of the plane carrying the tips, with the tips in lowered position.

35 In these views, the numeral 1 indicates a plane which is attached to the aircraft shown generally at A, by the posts 2. This plane is of practically the same length as the ordinary planes of the craft, but is of greater 40 width as it extends almost to the rear of the ship. Tips 3 are hinged to the edges of the plane 1, as shown at 4, and arms 5 are connected with the ends of each tip, one part of each arm extending upwardly and another 45 part downwardly. A pair of springs 6 is arranged adjacent each corner of the plane 1. These springs are connected by the rods 8 with the upper parts of the arms 5 and the rods and springs are supported by the posts

50 7. One spring of each of the front pairs of springs is connected to the arms 5 of the front tip and the other springs of these pairs are connected with the front arms 5 of the side

tips. One spring of each of the rear pairs of springs is connected with the arms of the 55 rear tip and the other springs of these pairs of springs are connected with the rear arms of the side tips. The springs hold the tips in horizontal position.

Cables 9 connect the lower parts of the 60 arms 5 with a hand lever 9' which is arranged where it can be manipulated by the pilot in the cockpit, said cables passing over guiding pulleys 10. Stop pins 11 are provided for limiting the movement of the tips from a 65 horizontal position, as shown in Figure 2, to an inclined position as shown in Figure 3.

From the foregoing it will be seen that when the parts are in normal position, the 70 tips form extensions of the plane 1 and the craft can be handled in the usual manner. If the craft should get out of control and start to fall, the pilot would grasp the lever 75 9' and pull upon the same, which would cause the cables acting upon the lower parts of the arms 5 to swing the tips downwardly into the position shown in Figure 3, so as to catch and hold the air under the plane 1 and thus give the effect of a parachute so that the craft would descend slowly and land without 80 damage.

It is thought from the foregoing description that the advantages and novel features of my invention will be readily apparent.

It is to be understood that I may make 85 changes in the construction and in the combination and arrangement of the several parts, provided that such changes fall within the scope of the appended claim.

What I claim is:—

90 In an aircraft, a horizontal plane connected therewith, tips forming extensions of the sides and ends of the plane, means for hingedly connecting the tips to the plane, arms connected with the ends of the tips and formed with upper and lower parts, springs connected with the plane and with the upper parts of the arms, cables connected with the lower parts of the arms, a hand lever arranged adjacent the pilot's seat and to which the cables are connected and stop means for the tips for limiting their movement from a horizontal position to an inclined position.

100 In testimony whereof I affix my signature.

HALLETT O. NORMAN.
